DESIGN FOR AN EYEGLASS SHADE

Frederick S. Lee, Los Angeles, Calif.

Application July 16, 1934, Serial No. 52,597

Term of patent 7 years

To all whom it may concern:

Be it known that I, Frederick S. Lee, a citizen of the United States, and residing at Los Angeles, in the county of Los Angeles and State of California, have invented a new, original, and ornamental Design for an Eyeglass Shade, of which the following is a specification, reference being had to the accompanying drawing forming a part thereof.

In the accompanying drawing, Fig. 1 is a front elevation of an eyeglass shade showing my design; Fig. 2 is a top plan view of the eyeglass shade; Fig. 3 is a section taken on line 3—3 of Fig. 1. I claim:

The ornamental design for an eyeglass shade as shown.

FREDERICK S. LEE.
